UNITED STATES PATENT OFFICE.

ERIK G. NYLANDER, OF CHICAGO, ILLINOIS, ASSIGNOR TO CAMEL COMPANY, OF CHICAGO, ILLINOIS, A CORPORATION.

DOOR MECHANISM FOR RAILWAY-CARS.

1,136,971.

Specification of Letters Patent. Patented Apr. 27, 1915.

Application filed July 14, 1913. Serial No. 778,890.

To all whom it may concern:

Be it known that I, ERIK G. NYLANDER, a citizen of the United States, and a resident of the city of Chicago, county of Cook, 5 and State of Illinois, have invented certain new and useful Improvements in Door Mechanism for Railway-Cars, of which I do declare the following to be a full, clear, and exact description, reference being had 10 to the accompanying drawing, forming part of this specification.

It is customary to provide railway freight cars with sliding doors suspended by trolley hangers attached to the upper edge of 15 the doors and adapted to travel upon rails extending above the doorways and secured to the side wall of the car.

The object of the present invention is to provide improved means for holding the 20 lower edge of the sliding door against pressure from the inside of the car and as well, also, against danger of being lifted to such extent as to displace the trolleys or hangers from the tracks.

25 The invention consists in the novel features of improvement hereinafter described, illustrated in the accompanying drawing, and particularly pointed out in the claims at the end of this specification.

30 In the drawing, Figure 1 is a view in cross section on line 1 of Fig. 2 through a portion of the door sill and side wall of a car, and through the lower portion of a sliding door having my invention applied 35 thereto, one of the retaining brackets being shown in side elevation. Fig. 2 is a view in front elevation of the parts shown in Fig. 1. Fig. 3 is a view in vertical section through the lower portion of a steel door embodying 40 my invention.

45 My invention may be applied in connection with wooden doors such as are now commonly employed for freight cars, or in connection with metal doors such as are used in certain types of cars. I have not deemed it necessary to illustrate the entire door and the means of suspending the same to permit it to slide back and forth across the doorway of the car, as any of the well 50 known types of hangers may be employed for this purpose.

Referring more particularly to Figs. 1 and 2 of the drawing, 5 designates the lower portion of the car door, to the bottom edge

of which is connected the channel bar 6, this 55 channel bar extending from front to rear of the door. Preferably, the channel bar 6 is provided with an upstanding member 7 whereby the bar is attached to the door by means of through bolts or rivets 8 that pass 60 through the lower portion of the door. Inside the channel bar 6 is preferably placed a wedge plate 9 having a beveled end 9^a and riveted to the channel bar at 10, the purpose of this wedge plate being to insure the 65 tight closing of the door.

Into the channel bar 6 projects the upper, inwardly extending end 11 of the bracket 12, this bracket being suitably attached, as by through bolts 13, to the side 70 wall of the car beneath the door sill or plate 14. The upper portion 11 of the guide bracket 12 is preferably arranged about midway between the top and bottom walls 75 of the channel bar 6, and this bracket is preferably reinforced by one or more strengthening ribs, as shown.

From the foregoing description it will be seen that as the door is moved back and forth, the guide bracket 12 setting within 80 the channel bar 6 serves to resist any outward thrust upon the door 5 and the bottom member or wall of the channel bar will prevent any excess lifting of the door to such extent as would endanger the slipping of 85 the trolley wheels or hangers from the overhead track. The channel bar 6 performs the further function of protecting the lower edge of the door and of guarding to a considerable extent the open space between the 90 bottom of the door and the sill 14. Thus, for example, if the door were not provided with the channel bar 6, any rain running down the outer face of the door might be blown around the lower edge and into the 95 car, whereas the channel bar not only protects the lower edge of the car door from the water but also serves to prevent rain, snow, or the like, from being blown into the opening between the bottom edge of the 100 door and the door sill 14.

The wedge plate 9 within the channel bar 6 serves to force the door inwardly toward the body of the car and thus insure the door opening being tightly closed. The wedge 105 plate 9 is placed at such a position within the channel bar that as the door is moved to approximately closed position, the inner

end 11 of the bracket 12 will bear against the inclined end 9^a of the wedge plate so that as the door reaches its closed position it will be forced closely in against the side 5 of the car.

In Fig. 3 of the drawing, I have shown how my invention may be used in connection with steel doors of freight cars. In Fig. 3, the body 5^a of the door is formed of plate metal the lower edge being bent to form the channel 6^a within which is secured the wedge plate 9, as in the construction hereinbefore described. Obviously, when the steel door is provided with a channel 15 bar 6^a at its lower edge, such channel bar will coöperate with a retaining bracket or brackets, as in the construction hereinbefore described, to hold the lower portion of the door against displacement.

In the drawings, I have shown only a single retaining bracket 12, but obviously, any desired number of retaining brackets may be employed, depending upon the length of the door. Manifestly, the precise 25 details above set forth may be varied; that is to say, the exact shape of the channel bar may be varied and the shape of the retaining bracket or retaining member may also be modified without departing from the 30 spirit of the invention.

Having thus described my invention, what

I claim as new and desire to secure by Letters Patent, is—

1. In a railway freight car, the combination with a sliding door, of an outwardly facing channel bar secured to the bottom of said door and covering the lower edge thereof, said channel bar having formed integral with its upper member a vertical flange secured to the outer face of the door, and a retaining bracket secured to the car body and having an upwardly and forwardly extending part projecting within said channel bar, substantially as described.

2. In a railway freight car, the combination with a sliding door, of an outwardly facing channel bar secured to the bottom of said door and covering the lower edge thereof, said channel bar having formed integral with its upper member a vertical flange secured to the outer face of the door, a retaining bracket secured to the car body and having an upwardly and inwardly extending part projecting within said channel bar and wedge plates of less thickness than the width of the horizontal members of said channel bar, substantially as described.

ERIK G. NYLANDER.
